SUPPORTING MEANS FOR SPEAKER VOICE COILS

Joseph M. Andrus, Chicago, Ill., assignor to Utah Radio Products Company, Chicago, Ill., a corporation of Illinois

Application August 7, 1939, Serial No. 288,786

3 Claims. (Cl. 179—115.5)

The invention relates to supporting means for a speaker voice coil and has as its general aim the provision of new and improved means for effectively supporting a voice coil assembly which is efficient and economical.

Supporting means for voice coil assemblies, sometimes termed "spiders" must have substantial rigidity in a plane normal to the axis of the voice coil for maintaining a proper spacing of the voice coil in the magnetic gap of the speaker. The supporting means must also have substantial flexibility in a direction axially of the voice coil to permit the coil and the parts assembled therewith to respond to fluctuations in the magnetic field. Furthermore, the supporting means should be so fashioned that air may pass freely through the supporting means.

An object of the invention is to provide a new and improved supporting means for a voice coil assembly adapted to be secured to the assembly on a plane normal to the axis thereof and having substantial rigidity in and flexibility transversely of said plane, and in which a large number of small perforations are thickly dispersed over the supporting means preferably in the arrangement of the interstices of a loosely woven material.

Another object is to provide a novel voice coil supporting means in which the separate elements of a loosely woven material are bonded together and the interstices of the material are open whereby a sheet of the material has an open grid form substantially rigid in the plane of the sheet and flexible in a direction transverse to said plane.

Other objects and advantages will become apparent in the following description and from the accompanying drawing, in which:

Figure 1 is a fragmentary front view of the central portion of a speaker having associated therewith a voice coil supporting means embodying the features of the invention.

Fig. 2 is a perspective view of a voice coil assembly and the supporting means.

Fig. 3 is a face view on a greatly enlarged scale of a section of the material from which the supporting means is fashioned.

Fig. 4 is a transverse sectional view through a sheet of such material.

While the invention is susceptible of various modifications and alternative constructions, I have shown in the drawing and will herein describe in detail the preferred embodiment, but it is to be understood that I do not thereby intend to limit the invention to the specific form dis-

closed, but intend to cover all modifications and alternative constructions falling within the spirit and scope of the invention as expressed in the appended claims.

5 In the drawing, the numeral 10 designates generally the central portion of a conventional type of speaker frame. As is well known, a voice coil assembly, comprising a cylindrical member 11 on which the voice coil (not shown) is wound, must be supported with respect to the magnetic gap of the speaker so that the voice coil is in properly spaced relation to the pole faces. In the present instance, the voice coil supporting means has been illustrated as being in the form of a circular member 12 which is centrally apertured to surround the cylinder of the voice coil assembly and to be secured thereto as by means of an axially extending flange 13 (Fig. 2). Peripherally, the member 12 is adhesively bonded or otherwise suitably secured to the frame.

20 The voice coil supporting means extends in a plane normal to the axis of the voice coil and, since the spaced relation of the voice coil in the magnetic gap must be preserved, the supporting means must be substantially rigid in its plane yet it must have substantial flexibility transversely of its plane or in the direction of the voice coil axis to permit the voice coil to respond accurately to magnetic variations. If desired, the 25 flexibility of the supporting means may be increased by providing near its outer periphery an annular rib 14. It is important that movements of the voice coil be substantially unimpeded and for this reason voice coil supporting means have 30 heretofore had various shapes and forms for minimizing the resistance offered by air to movement of the voice coil supporting means.

The present invention provides voice coil supporting means having substantial rigidity in its 35 plane and flexibility in a direction transversely thereof. Moreover, the supporting means has a large number of closely spaced small perforations over its surface area permitting substantially unimpeded flow of air through the supporting means 40 as the supporting means is flexed by movements of the voice coil assembly. I have found that by a novel process a loosely woven or open mesh fabric material can be treated to stiffen the separate elements or threads of the fabric and bond them together to obtain the required rigidity of the material in any direction in its plane without materially affecting its transverse flexibility and without closing the interstices of the fabric.

45 In obtaining these results, I prefer to employ 50 a material fashioned from a regenerated cellu-

lose, for example, cellulose acetate of the type used in the material which is known commercially as "Celanese." The regenerated cellulose should have the property of being soluble and of returning substantially to its original state upon evaporation of the solvent. It is preferred that a thermo-plastic cellulose acetate be used so that the axial flange 13 and the annular rib 14 may be quickly and conveniently formed in a die by the application of heat and pressure. The cellulose acetate "Celanese" is readily soluble in a number of well known solvents and is thermo-plastic.

"Celanese" may be obtained in the form of an open mesh woven fabric and each strand of the fabric is made up of a number of smaller threads. According to the process, the material is subjected to the action of a fluxing agent capable of softening each of the separate and individual elements and causing them to flux or bond together. As a result, the individual small threads in each fabric strand, as well as the fabric strands, are united integrally and produce a sheet of material having substantially the structure shown in greatly exaggerated form in Figs. 3 and 4. In these figures, the united strands are indicated at 15 and the open interstices at 16.

As examples of satisfactory cellulose acetate solvents, ethyl acetate, acetone and methyl acetate may be mentioned. However, these solvents act so rapidly on the material that it is quite difficult as a practical matter to control the fluxing action with any degree of uniformity. I prefer, therefore, to use as an ingredient of the fluxing agent some substance which in a sense dilutes the solvent in that the solvent action is retarded or delayed. As retarding agents, I have found that petroleum ether and carbon tetrachloride give satisfactory results. A fluxing agent composed, for example, of ethyl acetate or acetone with petroleum ether or of methyl acetate with carbon tetrachloride may be satisfactorily used to produce the desired fluxing of the individual elements of a "Celanese" material.

In the fluxing operation, it is noted that there may be a tendency of such cellulose acetate as is taken into solution to form an almost invisible film across a considerable proportion of the interstices of the material. I have found that this difficulty may be avoided by adding to the fluxing agent a quantity of a cellulose acetate solvent having a relatively slow evaporating rate which is effective, theoretically, to reduce the surface tension of the dissolved cellulose acetate. Hence, as the fluxed material is dried, the film across the interstices will collapse and the interstices will remain open. Among the suitable solvents for cellulose acetate which have a slow rate of evaporation are "Cellosolve" acetate and dichlor ethyl ether.

The following formulas are cited as examples of fluxing agents which will produce the desired results in a material formed of the cellulose acetate, "Celanese," the proportions being measured by volume:

Example 1

	Parts
Ethyl acetate	4
"Cellosolve" acetate	1
Petroleum ether	1

	Parts
Acetone	2
"Cellulose" acetate	1
Petroleum ether	2

Example 2

	Parts
Methyl acetate	3
Dichlor ethyl ether	1
Carbon tetrachloride	1

Example 3

After the material has been fluxed and dried to produce its unitary rigid structure, it may, if desired, be moisture proofed in any suitable manner as by applying a thin coating of wax to the material strands. Impregnation of the material with a four per cent (4%) solution of "Halo wax" in carbon tetrachloride will satisfactorily moisture proof the material.

After the material has been fluxed, dried and moisture proofed, it may be cut to a desired form, such as the circular disk shown in the drawing, and thereafter subjected to a forming operation to produce the axial flange 13 and the bead 14. This operation may be conveniently performed by subjecting the material to the combined action of heat and pressure in suitably formed dies. Where the material is "Celanese" the temperature and pressures required properly to form the material may be varied within rather wide limits as long as the temperature and pressure are varied inversely. For example, a combination of a pressure of 75 pounds at 375° F. may be varied to a combination of 500 pounds pressure at 210° F.

I claim as my invention:

1. A support for a speaker voice coil comprising a sheet of open weave fabric formed of an inherently thermoplastic material having the individual elements of each thread permanently bonded together and having each thread permanently bonded to the other threads at each point of crossing, said support having been subjected to a final forming operation under heat and pressure and being characterized by substantial rigidity in the direction of its plane and flexibility in a direction transverse to said plane.

2. A support for a speaker voice coil comprising a sheet of thermoplastic cellulose acetate material formed of a plurality of threads woven into a mesh fabric, the individual elements of each thread and the cross portions of all threads being permanently bonded together to provide a sheet rigid in the direction of its plane and flexible in a transverse direction, said support having been molded into final form by heat and pressure.

3. A spider for supporting the voice coil of a radio loud speaker comprising a corrugated cellulose acetate material formed of a plurality of threads woven into a fabric bonded together and molded into corrugated form by heat and pressure, the individual elements of each thread and the crossing portions of all threads being permanently bonded and the weave of the fabric being such as to provide openings in the interstices thereof after bonding, said spider being relatively rigid in the direction of its plane and relatively flexible in a transverse direction.

JOSEPH M. ANDRUS.
